UNITED STATES PATENT OFFICE.

FREDERICK W. ATKINSON, OF CHICAGO, ILLINOIS.

DESIGN FOR A RAIL-BOND.

SPECIFICATION forming part of Design No. 29,743, dated November 29, 1898.

Application filed October 17, 1898. Serial No. 693,837. Term of patent 7 years.

To all whom it may concern:

Be it known that I, FREDERICK W. ATKINSON, a citizen of the United States, residing at Chicago, in the county of Cook and State of Illinois, have invented and produced a new, useful, and original Design for a Rail-Bond, of which the following is a specification, reference being had to the accompanying drawings, forming part thereof.

Figure 1 is a plan view of a rail-bond, showing my design. Fig. 2 is a side view of the same.

The leading feature of my design consists in the bends or offsets in the connecting-strips which connect the end blocks of the bond, the outlines of which when viewed in plan lie wholly within the planes of the sides of the end blocks.

Reference-signs B C designate the end blocks of the bond, rectangular in general outline and having the projecting ends F G. The strips A connect the blocks B C, and said strips have bends or offsets D E intermediate

their ends, the bends or offsets D on one side being presented toward the bends or offsets E on the other side, whereby the outlines of the connecting-strips lie wholly within the planes of the two outer sides of the end blocks. The top surface of the end blocks B C, as viewed in plan in Fig. 1, is plane, and the surfaces of the edges of the connecting-strips A, which are presented toward the ends F G, lie in the same plane therewith.

Having described my invention, what I claim as new, and desire to secure by Letters Patent, is—

The design for a rail-bond as herein shown and described.

In witness whereof I have hereunto set my hand, this 20th day of September, 1898, in the presence of the subscribing witnesses.

FREDERICK W. ATKINSON.
